UNITED STATES PATENT OFFICE.

ALBERT GOLDSTEIN, OF NEW YORK, N. Y., ASSIGNOR TO INTERNATIONAL ELECTRIC PROTECTION COMPANY, A CORPORATION OF NEW YORK.

ELECTRICAL THERMOSTATIC ALARM SYSTEM.

977,295.

Specification of Letters Patent. Patented Nov. 29, 1910.

Application filed May 2, 1910. Serial No. 558,819.

To all whom it may concern:

Be it known that I, ALBERT GOLDSTEIN, a citizen of the United States, residing at New York, in the county of New York and State of New York, have invented a certain new and useful Improvement in Electrical Thermostatic Alarm Systems, of which the following is a specification.

The invention relates to an electrical thermostatic alarm system, and has for its object the prevention of false alarms, due to accidental troubles on the line.

The invention consists, first, in the combination whereby three changes must be produced in the circuit, such as two breaks and a make, or two makes and a break, before the alarm operates; and also in the construction of the thermostat whereby upon the movement of the diaphragm due to expansion of air within the case, said changes are caused. In this way, two accidental changes occurring on the line, such as a crossing, and then a separation of the wires—due, for example, to the wires swinging together and then swinging apart—is prevented from giving a false alarm.

In the accompanying drawings—Figure 1 is a cross section of my thermostat, and Fig. 2 is an electrical diagram of an alarm circuit including three of said thermostats located at different stations.

Similar letters and numbers of reference indicate like parts.

The circular case 1 comprises two flanged cup-shaped members 2, 3, between which the diaphragm 4 is received and held. Said diaphragm is to be made of thin sheet metal, preferably the thinnest sheet copper procurable, and may be corrugated and provided with a central contact boss 5. The member 2 is to be preferably made of steel much heavier than the member 3, so as to form the chief support for the device. The member 3 is preferably of a metal that is highly conductive of heat, such as copper, and as thin as will afford the necessary rigidity. The flange of member 3 has a corrugation 6 which enters a similar corrugation in the flange of member 2. The flange of diaphragm 4 is clamped between said corrugated members, so that the diaphragm is thus strained and a close air-tight joint formed between the parts. The member 3 may be secured by bending its circumferential edge 7 over the edge of member 2.

Centrally disposed in member 2 is a block 8 of insulating material, on which are two contact plates 9, 10. In the block is an opening through which loosely passes a metal rod 11 supported on a screw 12, which passes through a metal bridge piece 13, which normally rests on the contact plates 9, 10. The bridge piece 13 forms a nut for the screw 12 in which said screw may be adjusted by turning the milled head 14 so as to bring the lower end of rod 11 into desired proximity to the boss 5 on diaphragm 4. The contact plates 9, 10 are respectively connected to terminals of the circuit wire a , while the diaphragm 4 is connected to terminals of the circuit wire a' . On the contact plates 9, 10 are threaded posts 18, on which are nuts 19, between which nuts are clamped the contact pieces 20, so that said contact pieces can be adjusted nearer to or farther from the bridge piece 13.

Air vents 15 (dotted lines Fig. 1) are made in member 2 and communicate with the chamber therein on one side of the diaphragm. In the chamber in member 3 on the other side of the diaphragm is a tube 16 open at both ends and at its outer end communicating with an opening in the wall of said chamber.

The operation of the thermostat is as follows: The contact piece 11 is first adjusted in suitable proximity to the diaphragm 4. When the surrounding atmosphere increases in temperature, the heat is rapidly conducted through the thin metal wall of the chamber in member 3 and expands the air therein. This air can escape only through the tube 16 which is made long and of small cross sectional area as compared with the vents 15, so as to retard the air flow. On the other hand, the air in the chamber in member 2 on the other side of the diaphragm can escape more freely through the vents 15. The consequence is, that the expansion of the air in the chamber containing the tube is so quick as to be practically an impulse in the confined air body which, being communicated to the diaphragm 4, first moves it into contact with rod 11, thus producing a crossing from wire a to wire a' , and then the further upward movement of the diaphragm raises the rod 11 and bridge 13, first, to break contact between the terminal plates 9, 10, and then to close contact with the contact pieces 20. 110

In Fig. 2 the thermostat is shown in an alarm circuit.

The wires a, a' are line conductors connected to opposite poles of the battery A. 5 In the conductor a' is a magnet B which controls the two switch levers b and b' . The battery current normally energizes magnet B, so that a metallic circuit proceeds from one pole of battery A, by wire 10 a' , to magnet B, to contact point c , switch lever b' , and wire a back to battery. In the conductor a and on opposite sides of the battery A are two magnets C, D, which respectively actuate pivoted armatures E, F, 15 which are in bell-crank form. At the end of each vertical arm of the armatures E, F, are formed Z-shaped slots e, f , which receive pins G on the ends of the pivoted arms H. Said arms may fall by gravity to meet 20 contact points i, j , and so close a local circuit which includes a battery I and electric bell J.

In the circuit conductors a, a' at N, N' , N^2 are interposed as many of the thermostats, shown in Fig. 1, as there are stations from which it is desired alarms shall be given.

The operation is as follows: Assume the diaphragm of the thermostat at N, Fig. 2, to 30 be moved to close contact with its rod. This short-circuits magnet B. The switches b, b' then drop and close circuit at the points c^2 and c^3 . Circuit is then established through both magnets C, D, which attract their 35 armatures E, F to bring the upper portions of slots e, f in a more nearly vertical position. The pins G then drop until they reach the upper angles k of the slots. The diaphragm continuing to move under the air impulse, 40 lifts the contact rod 11 and bridge 13, thus breaking circuit in wire a at 9 and 10. Magnets C and D then fail, and the armatures E, F return to the position shown in the drawing. The pins G then descend to the 45 second angle 1 in slots e and f . The diaphragm still continuing its movement carries the bridge piece now out of contact

with points 9 and 10 into contact with points 20. The magnets C, D again attract their armatures, with the result that the slots e, f are placed so that the pins G can descend 50 the lowest incline, and thus permit the pivoted arms H to close at i and j the local circuit to the alarm J.

By reason of the aforesaid construction, 55 which requires, first, a make, then a break and then a make in the main circuit before the alarm can be operated, it is impossible for two abnormal changes in the electrical conditions to actuate said alarm. In this 60 way, false alarms from troubles on the line will be largely prevented.

I claim:

1. The combination in circuit of an electrical thermostat comprising a case, a diaphragm in said case and operated by air expansion therein, means controlled by said diaphragm for making successively three changes in the electrical condition of the circuit, and an alarm device operating only 70 after the third change in said condition.

2. The combination in circuit of an electrical thermostat comprising a case, a diaphragm in said case and operated by air expansion therein, means controlled by said diaphragm for first making, then breaking 75 and then making said circuit, and an alarm device operating only after said second make.

3. The combination in circuit of a magnet, a circuit closing switch controlled by said magnet to move over three successive portions of its path before closing circuit, and an electrical thermostat comprising a case, a diaphragm in said case and operated by air expansion therein, and means actuated by said diaphragm to control said magnet to cause said movement of said switch. 80

In testimony whereof I have affixed my signature in presence of two witnesses.

ALBERT GOLDSTEIN.
